HENRI CHIREIX, OF PARIS, FRANCE

DEVICE FOR ELECTRIC SOUND TRANSMISSION

Application filed November 1, 1929, Serial No. 403,963, and in France November 17, 1928.

The present invention is concerned with the combination and disposition of microphones for the purpose of electric sound transmission.

5 It is particularly, though not exclusively, applicable to the installation of broadcasting studios and for making phonographic records of musical concerts.

10 One of the advantages of this invention is the possibility of distributing the musicians of an orchestra in a semi-circle around the sound collecting microphone system at a distance relatively unfavorable in regard to the latter, yet without any undue loudening or 15 muffling of any of the instruments of the ensemble.

Another advantage obtainable through 20 this invention is the possibility it affords for a large number of performers to be engaged in a relatively small room without impairing the effect of the orchestral ensemble.

25 A third advantage consists in the avoidance of disturbing effects of stationary waves (strengthening or muffling certain tones).

These results are obtained, according to 30 the invention, by combining a number of microphones in such a manner that the different elements of this ensemble are grouped in a space which is small as compared to the space occupied by the orchestra. The sensitive surfaces of these microphonic elements are exposed in different directions, precautions being taken, on the other hand, to avoid that the elements cover each other or 35 are influenced by sound waves reflected from neighboring surfaces.

The invention will be better understood by referring to the attached figures and to the descriptions pertaining thereto which, by 40 way of example, indicate a possible arrangement. Of these figures

Figure 1 represents a plan view;

Figure 2 an elevation of the microphone arrangement; and

45 Figure 3 is a plan illustrating the location of the arrangement and of the performers in a hall.

According to Figure 1 two microphones 1 and 2 are placed back to back with their 50 sensitive faces turned out. Instead of this

arrangement a single microphone might be employed having two sensitive faces turned in opposite directions. Near this first group a third microphone 3 is placed with its sensitive face turned at right angles to the two others. A vertical sound-absorbing partition 4 is located behind the microphone 3. It has a bolstered surface to absorb the sound waves. Likewise there is a horizontal sound-absorbing partition 5 of the same qualities underneath the microphone ensemble.

55 Figure 2 shows the same elements in elevation. One perceives by looking at the figure that the microphone 3 is slightly elevated above microphones 1 and 2 so as not to be covered by the latter. The microphones are supported in the usual manner, for instance, on the legs 6 and 7, with the interposition of an insulating holder not depicted on the sketch.

60 Figure 3 indicates how a group of microphones 1, 2, 3 combined in accordance with the invention, may be located in a hall 8, shown in plan, supposedly of a rectangular shape. The musicians of the orchestra or the performing chorists are arranged in concentric rows as indicated on the sketch by dotted lines, for instance, 9.

65 The action of the microphones on the electrical apparatus to which they are connected, for example, modulation amplifiers, or recorders, is intensified by suitably arranged circuit elements such as parallel connections, transformer with multiple primary windings and common secondary winding, etc.

70 It is evident that under these conditions and owing to the arrangements which constitute the object of this invention the variations in effect of an instrument caused by its location in the hall are negligible, notwithstanding the close proximity between the performers and the microphone system. On the other hand, the noisy effect of the stationary waves is avoided on account of the fact that the microphones are not rigorously secured in one place. Finally, the presence of sound-absorbing partitions has the effect of exposing the microphones mainly to direct sound waves at the exclusion of waves reflected from neighboring surfaces, floor and walls.

It must be understood that the invention is by no means limited to the arrangement as shown in this example; it is, in fact, possible to increase the number of microphones used 5 beyond three arranging them in such a manner that they will be turned toward intermediate points of the orchestra, and not only toward the two ends and toward its center as proposed in the example considered above. 10 Another disposition would be to have the orchestra arranged so that it will completely surround the group of microphones and to replace the microphone 3 with a double-faced microphone or with two microphones back to 15 back similar to the system of microphones 1 and 2. In this case partition 4 evidently has to be omitted.

I claim:

20 A sound collecting unit for collecting sound emitted by a source or group of sources occupying a zone around said unit which is large relative to the dimensions of the unit, comprising a group of microphones facing in different directions toward said large zone and 25 grouped within a space which is small relative to the size of said zone, and sound absorbing material positioned adjacent the back of said microphones and additional sound absorbing material positioned adjacent the bottom of said microphones, all of said sound absorbing material being at a distance which is small relative to the dimensions of said large zone.
